(57) **CLAIM**

The ornamental design for an automatic card reader, as shown and described.

DESCRIPTION

FIG. 1 is a first perspective view of an automatic card reader; FIG. 2 is a second perspective view of the automatic card reader;

FIG. 3 is a front view of the automatic card reader;

FIG. 4 is a rear view of the automatic card reader;

FIG. 5 is a left side view of the automatic card reader;

FIG. 6 is a right side view of the automatic card reader;

FIG. 7 is a top view of the automatic card reader;

FIG. 8 is a bottom view of the automatic card reader;

FIG. 9 is a partially enlarged view of part I of the automatic card reader as shown in FIG. 1;

FIG. 10 is a partially enlarged view of part II of the automatic card reader as shown in FIG. 2;

FIG. 11 is a partially enlarged view of part III of the automatic card reader as shown in FIG. 2; and,

FIG. 12 is a partially enlarged view of part IV of the automatic card reader as shown in FIG. 5.

The ornamental design which is claimed is shown in solid lines in the drawings. The broken lines in the drawings depict portions of the automatic card reader that form no part of the claimed design.
